United States Patent Office.

ALFRED ARNEMANN, OF GUTTENBERG, IOWA.

Letters Patent No. 81,862, dated September 8, 1868.

IMPROVEMENT IN SAFETY-ATTACHMENTS FOR POCKETS OF APPAREL.

The Schedule referred to in these Letters Patent and making part of the same.

TO ALL WHOM IT MAY CONCERN:

Be it known that I, ALFRED ARNEMANN, of Guttenberg, in the county of Clayton, and State of Iowa, have invented a new and useful Improvement in Pocket-Book Protectors; and I do hereby declare that the following is a full, clear, and exact description thereof, which will enable others skilled in the art to make and use the same, reference being had to the accompanying drawings, forming part of this specification, in which—

Figure 1 represents a side view of my improved pocket-book protector.

Figure 2 is a transverse section of the same, taken in the plane of the line $z z$, fig. 1.

Similar letters of reference indicate like parts.

This invention relates to a new device for retaining pocket-books or other articles in the pockets, or on the wearing-apparel, for the purpose of preventing their being lost or fraudulently abstracted.

The invention consists of a spring-catch, attached to the pocket-book, and of a wire clasp, fastened to the pocket or garment. The spring-catch can be easily fastened to the clasp, whereby the pocket-book will be securely locked in the pocket or to the garment. By touching a knob that projects from the catch, the hook can be easily released again whenever desired, although it will be impossible that another person can release it without the wearer noticing it.

A, in the drawing, represents a wire clasp, made of one or two pieces, and provided with one pointed end, a , and with a loop, b , at the other end.

The pointed end can be easily pierced through the inner or outer side of a pocket or other portion of a garment, to fasten the clasp thereto, and the pointed end can then be put through the eye b , as in fig. 1, to lock the clasp.

B represents a sheet-metal plate, bent as in fig. 2, and fastened with both ends to the opposite sides of a pocket-book or other article, so that it projects from one edge of the same.

To one side of the plate B is fastened a spring, c , which carries at its outer end a hook, d , that fits through a slot in the plate B, as clearly shown in fig. 2.

e is a pin, projecting from the spring c through the body of the plate B, and is provided with a knob or handle, f , at its outer end. By pushing against the knob f , the hook will be forced back.

The pocket-book is fastened to the clasp A by pressing the outer edge of the hook against the bow of the clasp, whereby the hook will be forced back to allow the wire to come between the two projecting arms, g h , of the plate B.

The hook will then, by the action of the spring c , be forced in again to fit over and lock the wire A, as is clearly shown in fig. 2. The pocket-book can then only be released by pressing against the knob f , whereby the hook, as aforesaid, will again be forced back.

The hook can either be suspended, as shown in the drawing, or it can be fastened to the suspended clasp by holding the catch downward, in which case the clasp should be fastened in the lower part of the pocket.

This device is simple, cheap, not cumbersome, and entirely efficient.

Having thus described my invention, I claim as new, and desire to secure by Letters Patent—

A pocket-book protector, consisting of the wire clasp A, and of the plate B, spring c , hook d , and knob f , all arranged and operating substantially as herein shown and described.

ALFRED ARNEMANN.
